EZEKIEL F. WHITE, OF HARTFORD, CONNECTICUT

FLEXIBLE DRIVING MEANS

Original application filed January 18, 1928, Serial No. 247,543. Divided and this application filed November 25, 1929. Serial No. 409,738.

This invention relates to flexible driving means, more particularly, though not exclusively, intended for driving a centrifugal element, such as a rotatable body, adapted under high speed to seek its natural center of rotation, one object of the invention being to provide a simple driving mechanism through which a body may be rotated at a relatively high speed with a minimum of noise, vibration and power consumption and with assurance of long life and durability in respect to the bearings and other parts subject to wear.

The invention as herein described is shown in its application to a liquid fuel, centrifugal burner, but it will be evident that various applications thereof may be made and uses other than that herein described.

This application is a division of my prior co-pending application, Serial No. 247,543, filed January 18, 1928, no claim being made herein to the features of the burner alone or in combination.

The invention will be best understood by reference to the following description when taken in connection with the accompanying illustration of one specific embodiment thereof, while its scope will be more particularly pointed out in the appended claims.

In the drawings:

Fig. 1 is a sectional elevation illustrating the centrifugal atomizing element and the driving mechanism therefor, as well as other parts of the burner apparatus which are located in or adjacent the combustion chamber of the boiler or other heater;

Fig. 2 is a plan view of the driving mechanism with the atomizing cup, its driving spindle and the oil feed pipe removed;

Fig. 3 is a sectional elevation on an enlarged scale, taken through the bottom of the main driving shaft, showing the provision for circulating the lubricant;

Fig. 4 is a section in plan taken on the line 4-4 in Fig. 3;

Fig. 5 is a sectional plan view of the atomizing member looking from beneath and taken on the line 5-5 in Fig. 1;

Fig. 6 is an enlarged, elevational view of the flexible spring driving connection be-

tween the main driving shaft and the atomizing spindle;

Fig. 7 is a detail showing the method of bolting the bearing support to the casing; and

Fig. 8 is a detail showing in elevation a portion of the triple spring driving connection between the driving shaft and the driven spindle.

Referring to the drawings, I have there shown for illustrative purposes one embodiment of the invention applied to a centrifugal liquid fuel burner, the liquid fuel, for the purpose of description, being herein assumed to be oil.

Referring to the drawings in detail, the burner comprises a centrifugal atomizing member designated generally at 11 which is located in the combustion chamber of the heater and is driven to rotate at high speed about an upright axis through appropriate gearing by means of a horizontal, relatively low speed, electric motor 13 mounted on the base plate 15. The armature shaft 17 of the motor carries at its end a worm gear 19 located within the casing 21 which is secured to the end of the motor frame, the gear 19 meshing with the worm 23 secured to the upright drive shaft 25.

The drive shaft 25 is mounted to rotate in upper and lower bearings 27 and 29, each of which is in the form of a sleeve having a spherical enlargement represented at 31 and 33, the latter being seated each in a spherical recess in the supporting casing 35. The bearing sleeves 27 and 29 are provided with pins 37 engaging recesses in the casing 35 which prevent the sleeves from turning about the axis of the shaft 25 but permit a slight, limited, rocking movement of each bearing sleeve in its socket to permit the sleeve to adapt itself to slightly different axial positions.

In assembling the parts, the supporting casing 35, with the sleeves and shaft assembled therein, is inserted through an opening in the top of the casing 21 and is secured thereto by the flanged plate 39 which is bolted to the casing by means of the bolts 41 (Fig. 2), the worm being brought into mesh with the teeth of the worm gear.

The holes in the flanged plate 39 through which the bolts 41 pass (see Fig. 7) are of larger diameter than the bolts themselves, so that a certain amount of clearance is left.

5 Accordingly, after the apparatus has been assembled the plate 39 with the supporting casing can be shifted within a limited range and the worm adjusted in any direction with relation to the gear 19 to secure the position 10 of best interengagement. In practice the final adjustment of the worm with relation to the worm gear can be made after the apparatus has been completely assembled and the motor operated, the flanged plate, with 15 the bolts only partly tightened, being then tapped into the position where the smoothest and most quiet running conditions are secured. When this position is found, the bolts are set up tight and if desired the plate 20 may be pinned in place.

The spherical supports for the worm shaft bearings provide a certain amount of self adjustment for the worm shaft, permitting the worm to adapt itself to the exact alignment required and also allowing for any flexing of the shaft through its engagement with the worm, thus preventing binding and serving to minimize the wear on the bearings, while at the same time providing bearing 25 contact for the shaft for the full length of the bearings. This adjustment of the main drive shaft and its self adaptability materially decrease the noise and vibration, add to the life and durability of the apparatus, and 30 reduce the power required to operate the burner.

The gear is driven in the direction of the arrow shown in Fig. 1, so that when the burner is in operation the engagement of 40 the gear with the worm tends in large measure to offset the weight of the drive shaft, atomizing member and other driven parts, thereby relieving the bearings of a substantial amount of frictional wear and further reducing the 45 power required to drive the burner.

Referring to the driving connections for the centrifugal atomizer, the latter is provided with the driven spindle 51 which is rotated within the upright casing 53 by a 50 driving connection to the main drive shaft, hereinafter described. The driven spindle rotates in a bearing 55 of substantial length, the bearing being in the form of a sleeve provided with a spherical enlargement 57 55 which rests in a spherical recess in the casing 53, so that the bearing is capable of moving freely within reasonable limits on its spherical seat, there being provided elsewhere a substantial clearance between the sleeve and 60 the casing to permit such movement. The bearing sleeve 55 is prevented from turning by the pin 59 which permits, however, the necessary movement of the bearing. The spherical seat on which the movement of the 65 spindle takes place is located well below

the center of gravity of the atomizing cup, the latter in the illustrated form of the invention having its center of gravity in approximately the plane of the bottom of the hereinafter described head 71.

70

Referring now to the driving connection between the spindle 51 and the driving shaft 25 (see Fig. 6), the spindle, which is in a position of substantial alignment with the shaft, is connected to be driven thereby through a yieldable connection, permitting the spindle and its bearing 55 a certain freedom of movement so that the atomizer may automatically adjust its center of rotation, the extent of such movement, however, being limited by its relation to the drive shaft.

75

For this purpose the lower end of the spindle is tapered at 61 for a substantial distance and has applied thereto a coiled connecting spring 63, the opposite end of the spring being applied to a similarly tapered but closely opposing end 65 of the drive shaft 25.

85

Owing to the small scale of the drawing, a conventional showing of a single spring only is made in Fig. 1. While a single or a double wound spring may be employed, I preferably employ a triple wound spring, that is to say, a spring wound from three separate pieces of spring wire with parallel and adjacent convolutions, this preferred form of 95 spring being shown in Figs. 6 and 8.

90

The inside diameter of the spring is preferably somewhat less than the greatest diameter of the tapered portions of the shaft and spindle and somewhat greater than the 100 smallest diameter thereof. When assembled, and with the atomizer at rest, the outer ends of the spring are distended and tightly grip the tapered portions of the driving and driven members for a substantial part of 105 their length, the intermediate part of the spring retaining its normal shape and diameter and clearing the tapered walls. The direction of the spring winding is such that when the burner is started up the spring 110 tightens its grip on both the driving and driven members and, under the torque of the driving motor, the open part of the spring closes in and, in whole or in part, also wraps about and grips the tapered wall. In starting the torque is several times the normal running torque, so that the action of the middle portion of the spring is first to wrap about or close in on the tapered walls, yieldably enforcing an alignment of the driving 115 and driven spindles, but to open up more or less and release the adjoining portions of the tapered driving and driven members as the critical speed is reached, allowing the atomizing member to float or seek its natural center of rotation.

115

In assembling the parts, the tapered ends of the two members can be readily forced and twisted into engagement with the spring and the latter provides an adequate driving con- 130

nnection between the driving and driven members, but permits the driven spindle to have the described movement or adaptation on its bearing seat 57 when it is driven at high rates 5 of speed.

It is desirable at all times, and particularly in starting up the rotation of the atomizer, that means should be provided for yieldably centering the driven spindle or drawing

- 10 it into a position of true axial alignment with the driving spindle; also that some means should be provided for limiting the extent of the movement of the spindle away from its position of alignment. Otherwise 15 vibration and unnecessarily wide and uncontrolled rocking or swaying of the atomizer and its spindle may result, and if initiated at starting it is apt quickly to get out of control with disastrous results.

20 To this end the ends of the two shafts are tapered as described so as to provide two tapered aligned seats for the spring. The spring or springs are thereby maintained in true axial alignment under all conditions

- 25 and variations of torque. In the case of a spring forced about two adjoining, truly cylindrical shaft portions of slightly greater diameter than the inside diameter of the spring, each distended portion of the spring 30 surrounding the shaft is concentric with the shaft but the intermediate portion which surrounds neither shaft is eccentric to the adjoining shafts. This creates an unbalanced condition, throwing the shafts out of alignment, 35 which condition is eliminated under all conditions of torque through the use of the tapered spring-engaging portions.

A plurality of springs, and preferably three, is also employed for this purpose, 40 since a single spring in wrapping about the shaft at starting provides a yielding resistance variable in different directions due to the characteristic of the spring. Through the use of a triple wound spring, however, 45 the three separate windings may be so adjusted and disposed with relation to each other that in the case of each tapered shaft the final points of contact between the shaft and the three spring members may be located 50 120° apart giving a balanced condition and an equal yielding resistance in all directions and under all conditions.

To limit the extent of movement of the driven spindle from its aligned position, the 55 tip of the spindle is reduced in diameter at 67 and this reduced end enters within an opening 69 in the tip of the driving shaft, there being provided a small but sufficient amount of clearance to permit the necessary

- 60 movement of the spindle as the atomizer seeks its natural center of rotation at high speeds.

In practice it is found that the balancing of the cup can be so closely approximated in 65 its initial construction, that, although some

movement of the driving spindle is necessary to insure perfectly smooth running, such movement may be so slight that a relatively small clearance in the recess 69 will answer.

In operation the resilient, triple wound, 70 spring connection, in cooperation with the tapered gripping portions of the two opposed shafts, tends to draw the two shafts yieldably into concentric or aligned relation, preserving such relationship when the apparatus starts into operation and tending at all times yieldably to restore such relationship if it is departed from. At the same time it provides a resilient connection permitting slight displacement of the spindle 75 from an exactly aligned position and permitting the slight gyratory movement necessitated by the gyrostatic effect of the high speed, centrifugal atomizing member. The effect of the spring driving connection is also 80 to cushion the shock between the cup and the motor, preventing the effect of irregularities in the driving of the motor from being transmitted to the cup.

Referring to the construction of the centrifugal atomizing cup, the latter is herein provided with a head 71 which projects into the combustion chamber, the head being of substantial mass and preferably constructed of a non-ferrous metal, such as aluminum or 85 brass, to provide a good conductor of heat.

Depending from the head and secured thereto is an annular oil receiving cup 73 having a trough-like bottom 75 in which the oil is adapted to be delivered by means of 90 the stationary delivery pipe 77 entering through the annular opening in the bottom of the cup between the rim thereof and the casing 53. The sides of the cup are flared 95 slightly upwardly and outwardly, so that when the atomizer is rotated the oil delivered to the trough 75 passes in the form of a thin film up the side of the cup and through a slot 79 formed between the sides of the cup and the edges of the head 71. The head is beveled or undercut at 81 to provide an escape 100 for the oil, there being left, however, a series of radial ribs 83 (see Fig. 5) through which the cup is fastened to the head by means of 105 rivets 85. The upper rim of the cup itself 110 is provided with a lip 87 which, in conjunction with the beveled edge of the head, forms the slot 79 and directs the air radially outward at a slight upward inclination while the atomized oil is projected tangentially from 115 the cup and in a horizontal plane.

The described burner may be employed in connection with air supply passages arranged in any suitable manner. Herein the bottom of the combustion chamber is formed by the 120 plate 89 supported on the base 15 by posts 91 (one of which only is shown) and carrying the wall 93 in the form of a truncated cone. On the top of the cone shaped wall 93 there is supported an air control casing 125 130

95 having an annular air admission passage 97 about the upright casing 53 for the atomizing cup spindle and adapted to deliver air immediately beneath and around the atomizing element. The air control casing is also provided with a plurality of additional air supply openings 99, the available area of which may be regulated by means of an adjustable damper ring 101 so that additional 10 air may be admitted from beneath the plate 89 through the air space 103 and the air openings 99. Above the air control casing 95 there is also provided a deflector plate 105 which rests on the casing by means of 15 several radial ribs 107 and serves to deflect the air entering through the openings 99 so that it passes into the combustion chamber in part about the outer edges of the deflector plate and in part through the central opening 20 109 in the deflector plate, where it commingles with the centrally fed air and passes in and about the atomizing member.

In the operation of the burner, the centrifugal atomizing member is driven at a high 25 rate of speed, for example, seven or eight thousand revolutions per minute. The oil delivered to the cup is thereby discharged through the annular slot 79, entering the combustion chamber tangentially in the form 30 of an atomized horizontal disk-like sheet. The air entering centrally about the atomizer through the opening 109 is augmented by that entering about the edges of the plate 105 and provides a layer of air underlying the sheet 35 of atomized oil. The air passing through the cup and the slot 79 is deflected above the sheet of atomized oil and provides an overlying layer of air, the effect being to produce an atomized sheet of oil between two layers of 40 air. The action of the burner provides a circulation of the upper air layer so that a substantial part of the hot, burned gases are returned back into the flaming mass, raising its 45 temperature of combustion.

Any of the usual methods of feeding the oil to the atomizing cup or controlling and regulating the oil feed in response to the requirements of the burner as well as controlling and regulating the action of the burner 50 and the motor may be employed, and since these are well known no attempt is made to illustrate the same. The oil is herein supplied to the pipe 77 through the connection 111 and inlet passage 113 by means of any suitable 55 feeding devices.

In the operation of the burner, the centrifugal atomizing element operating at high speed quickly finds its natural center of rotation. Any slight divergence of the axis of 60 the spindle 51 from its required position is immediately corrected by the movement of the spindle axis, the bearing 55 adapting itself to this condition by a slight movement on its ball seat 57 and the resilient connection 65 between the driving shaft and the spin-

dle permitting this movement of adaptation to readily take place. Unnatural or unnecessary oscillations of the cup spindle, however, are prevented by the relationship of the reduced end 67 of the driving spindle to the 70 recessed end of the driving shaft, the play between these two members, however, being sufficient to permit all necessary movements of adaptation. When the centrifugal member has been brought up to speed it runs smoothly and noiselessly in its bearings, operating 75 in similarity to the spinning action of a top, and the spindle and shaft will run with a minimum of bearing wear.

Preferably the driving mechanism herein, 80 including also the motor, is resiliently mounted, there being provided for this purpose the four springs 115, 117, 119 and 121 (Fig. 2), each seated in a socket 123 (Fig. 1) in the base plate 15 and supporting the motor and 85 casing 21 by means of studs 125 preferably threaded into the bottom of the motor frame and casing respectively so as to be capable of adjustment. When the apparatus is assembled, the studs are adjusted to secure the best 90 possible vertical alignment of the driving shaft. During the operation they provide a resilient support for the entire driving mechanism.

To assure lubrication for the driving 95 mechanism, the bottom of the casing 21 forms a well in which there is maintained a quantity of lubricating oil, the bottom of the supporting casing 35 being immersed in the lubricant and the rotation of the driving 100 shaft serving to circulate this oil through the bearings and other parts.

For this purpose it will be seen that the bearing support for the drive shaft terminates short of the bottom of the casing so that the oil has access to it. In the bottom of the casing 35 there is provided an oil chamber 127 (Figs. 3 and 4) surrounding the bottom 105 of the drive shaft 25, the lower end of which is formed with four radial slots 129. The bottom of the casing is closed by a plate 131 having a central opening 133, the plate being covered by a gauze screen 135 retained by a holding plate 137. The slotted lower end of the drive shaft acts as a centrifugal pump, drawing the oil in through the central opening 133, discharging it radially into the oil chamber 127 and thence through the discharge passage 139 by which it is carried up 110 through the bearing support 35 and through a registering passage 141 (Fig. 1) in the casing 53, being delivered between the spindle 51 and the spindle bearing 55 about the pin 59. The priming and operation of this pump are assisted by a baffle wall which is in the form 115 of a pin 143 (Fig. 3) located in the oil chamber to divert the oil into the passage 139.

The upper end of the bearing 55 is surrounded by a thimble 145 secured to the spindle to prevent the escape of lubricating oil 120

into the cup about the spindle, and the top of the casing is also protected by a small shield 147 secured thereto also to prevent the escape of lubricant and to preclude the possibility of fuel oil getting into the lubricating oil. The lubricating oil accumulating in the upper part of the casing 53 is drained through an oil groove 149 formed in the bearing sleeve 55 and, together with the oil gravitating from the spindle, passes down within the casing between the drive shaft 25 and its bearings, the excess oil being discharged through the groove 151 into the casing and onto the worm wheel 19. During the operation of the burner, therefore, there is a constant circulation of the lubricating oil from the casing to the bearings of the spindle, thence to the bearings of the drive shaft, the worm and the worm wheel.

Since the head 71 of the atomizer is formed of non-ferrous, heat-conducting metal, the heat which it acquires is conducted through the body of the head to the underside thereof and dissipated quickly to the air passing through the cup. This keeps the head relatively cool and raises the temperature of the air passing through the slot 79. The ribs 83 act as radiating vanes which materially increase the transference of heat from the head to the incoming air. The capacity of the head 71 to dissipate the heat quickly to the air circulating beneath and around the same enables the head to be run below the coking temperature of the oil. This prevents the coking or carbonizing of the oil, which has been a fault with atomizers provided with heads of ferrous metal and particularly when employed with oil carrying more or less cylinder stock or having an asphaltum or paraffin base, the high temperature at which such atomizers must be run causing accumulations of carbon which interfere with atomization and tend to throw the cup out of balance.

It will be observed that the spring driving connection is not only located remote from the effect of any high temperature, but is protected within the casing 53 where it is also subjected to the cooling effect of the circulating lubricant, and that the bearing 55 for the spindle 51 is also protected within the casing and similarly subjected to the cooling action of the lubricant. Due to the self cooling capacity of the non-ferrous head 71 in conjunction with the air circulation provided, these parts, and particularly the bearing 55, are also protected against the effect of any high temperature.

While I have herein shown and described for the purpose of illustration one specific embodiment of the invention, it is to be understood that extensive deviations may be made therefrom and widely different relationship of the various parts described may

be had, all without departing from the spirit of the invention.

Claims:

1. The combination with a freely rotatable body adapted to seek its natural center of rotation, of a spindle rigidly connected to drive the body, a journal bearing member for the spindle in which the latter is rotatably mounted, a separate driving shaft, a resilient spring connection between the shaft and the spindle, and a spherical bearing support on which the bearing member is movable and about which the gyratory movement of the spindle may take place. 70
2. The combination with a freely rotatable body adapted to seek its natural center of rotation, of a driving connection permitting the latter to seek its natural center of rotation and comprising a shaft rigidly connected to drive the body, a journal bearing for the shaft in which the latter is rotatably mounted, a spherical seat on which the bearing is movable, permitting gyratory movement of the shaft about said seat, a separate driving shaft and a resilient driving connection between the driving shaft and the shaft for said rotatable body permitting such gyratory movement with relation to the driving shaft. 80
3. The combination with a rotatable body freely rotatable about an upright axis and adapted to seek its natural center of rotation, of a depending spindle rigidly secured to said body to drive the same, a journal bearing member below the body and below the center of gravity thereof in which bearing member said spindle is rotatable, said spindle having an end protruding below the bearing member, a driving shaft separate from but normally aligned with the protruding end of said spindle and presenting an end adjacent the end of the spindle, a yielding driving connection between the spindle and shaft comprising a coiled spring in gripping engagement with the outside walls of the adjacent ends of the spindle and shaft, journal bearings for said driving shaft, a rigid casing enclosing said spring and providing support for the journal bearings of said driving shaft and providing also a support on which the journal bearing member for the spindle is movable to permit gyratory movement of the spindle axis, and means to drive the driving shaft. 90
4. The combination with a rotatable body adapted to seek its natural center of rotation, of a spindle rigidly connected to said body to drive the same, an elongated journal bearing sleeve in which said spindle is rotated, said spindle having an end protruding through said sleeve, a spherical seat in which said sleeve is mounted to permit gyratory movement of the spindle, a separate driving shaft normally aligned with the protruding end of the spindle and presenting an end adjacent the end of the spindle, a yielding 100
5. The combination with a rotatable body 105
6. The combination with a rotatable body 110
7. The combination with a rotatable body 115
8. The combination with a rotatable body 120
9. The combination with a rotatable body 125
10. The combination with a rotatable body 130

driving connection between the spindle and the shaft and acting to resiliently restrain excessive gyrations of the spindle about said spherical seat as a fulcrum.

5. The combination with a rotatable body freely rotatable about an upright axis and adapted to seek its natural center of rotation, of a depending spindle rigidly secured to said body to drive the same, a journal bearing member below the body and below the center of gravity thereof in which bearing member said spindle is rotatable, said spindle having an end protruding below the bearing member, a driving shaft separate from but normally aligned with the protruding end of said spindle and presenting an end adjacent the end of the spindle, a yielding driving connection between the spindle and shaft comprising a coiled spring in gripping engagement with the outside walls of the adjacent ends of the spindle and shaft, journal bearings for said driving shaft, a rigid casing enclosing said spring and providing support for the journal bearings of said driving shaft and providing also a support on which the journal bearing member for the spindle is movable to permit gyratory movement of the spindle axis, means to drive the driving shaft, and means for circulating fluid through said casing from said journal bearing member and said spring.

6. The combination of a rotatable hollow open bottomed body adapted to seek its natural axis of rotation, of a driving spindle rigidly secured to and depending from said body, a closed supporting and fluid containing housing surrounding said spindle and extending up through the open bottom end of said body, a journal bearing within said housing in which said spindle is rotatably mounted, a spherical seat in said housing in which said journal bearing is loosely supported and is capable of free rocking movement to permit gyrations of said body as it passes through its critical speed, a separate driving shaft spaced from and in axial alignment with said housing, bearings for said driving shaft mounted in said housing and a resilient driving connection between said shaft and spindle acting to yieldingly restrain excessive gyrations of said body about said seat as a fulcrum.

7. In a centrifugal machine of the class described in combination, a rotatable body and driving unit therefor, permitting said body to assume its natural axis of rotation at high speeds, said unit comprising a substantially tubular housing, a spindle within said housing and rigidly connected to said body to drive the latter, a journal bearing for the spindle in which the latter is rotatably mounted, a spherical seat on the bearing and cooperating spherical support in the housing for pivotally supporting said spindle and body to permit free rocking movement of the

latter as it passes through its critical speed, a separate driving shaft journalled in said tubular housing, and resilient driving connections between the shaft and spindle for imparting rotation of the former to the latter and also acting to exert a resilient restraining force against the end of the spindle to restrain excessive gyrations of the spindle about its point of pivotal support as a fulcrum.

8. The combination with a rotatable body freely rotatable about an upright axis and adapted to seek its natural center of rotation, of a depending spindle rigidly secured to said body to drive the same, a journal bearing member below the body, in which bearing member said spindle is rotatable, said spindle having an end protruding below the bearing member, a driving shaft separate from but normally aligned with the protruding end of the spindle and presenting an end adjacent the end of the spindle, a yielding driving connection between the spindle and the shaft, journal bearings for said driving shaft, a support positioned below the center of gravity of said body and between the latter and said yielding driving connection and presenting a support on which the journal bearing member for the spindle is movable to permit gyratory movement of the spindle axis, said support providing a center of gyration for said spindle and serving as a fulcrum through which said yielding driving connection is adapted to act to restrain excessive gyrations of the body, and means to drive the driving shaft.

9. The combination with a rotatable body adapted to seek its natural center of rotation, of a driven member connected to said body to drive the same, means providing a gyratory movement of the driven member about a center between the center of gravity of the body and the end of said member, a driving member, said driving and driven members having tapered ends separated but normally in closely aligned relationship, the end of the driven member being movable laterally with relation to the end of the driving member to permit said gyratory movement of the driven member, and a driving and aligning connection between said members comprising a coiled spring connecting said driving and driven members.

10. The combination with a rotatable body adapted to seek its natural center of rotation, of a driven member connected to said body to drive the same, means providing for gyratory movement of said member about a center between the center of gravity of the body and the end of the driven member, a driving member, the ends of said driving and driven members being separated but normally in closely aligned relationship and the end of the driven member being movable laterally with relation to the end of the driving member to permit said gyratory movement of the

driven member, a resilient driving connection between said members comprising a coiled spring, and means to limit the lateral movement of the driven member with relation to the driving member.

11. The combination with a body rotatable about an upright shaft and adapted to seek its natural center of rotation, of an upright driven shaft connected to said body to drive the same, means providing for gyratory movement of the shaft about a center between the center of gravity of the body and the lower end of the shaft, an upright driving shaft, said driving and driven shafts having 10 tapered ends in separated but closely aligned relationship and the end of the driven shaft being movable laterally with relation to the end of the driving shaft to permit said gyratory movement of the driven shaft, and a 15 driving and aligning connection between the shafts comprising a coiled spring gripping said tapered portions, said body and shaft being axially free to rest on and move with said spring, whereby the latter serves as a 20 resilient driving, aligning and supporting member.

12. The combination with a rotatable body adapted to seek its natural center of rotation, of a driven member connected to said body 30 to drive the same, means providing for gyratory movement of the driven member about a center between the center of gravity of the body and the end of said member, a driving member, said driving and driven members 35 having tapered ends, separated but normally in closely aligned relationship, the end of the driven member being movable laterally with relation to the end of the driving member to permit said gyratory movement of the driven 40 member, and a driving and aligning connection between said members comprising a coiled spring gripping said tapered portions, the spring when unstressed being of lesser inside diameter than the larger portions of 45 said tapered ends and of greater inside diameter than the smaller portions of said tapered ends.

13. The combination with a rotatable body adapted to seek its natural center of rotation, 50 of a driven member connected to said body to drive the same, means providing for gyratory movement of said member about a center between the center of gravity of the body and the end of the driven member, a driving member, said driving and driven members having ends separated but normally in closely aligned relationship, the end of the driven member being movable laterally with relation to the end of the driving member, and 55 a driving and aligning connection between said members comprising a spring engaging the adjacent ends of said driving and driven members and adapted to provide a yielding 60 resistance to the movement of the driven 65

member away from a position of axial alignment substantially uniform in all directions.

14. The combination with a rotatable body adapted to seek its natural center of rotation, of a driven shaft connected to said body to 70 drive the same, means providing for gyratory movement of the shaft about a center between the center of gravity of the body and the end of the shaft, a driving shaft, said driving and driven shafts having tapered ends, separated but normally in closely aligned relationship, the end of the driven shaft being movable laterally with relation to the end of the driving shaft to permit said gyratory movement of the driven shaft, a driving and 75 aligning connection between the shafts comprising a coiled spring gripping said tapered portions, the spring when unstressed being of lesser inside diameter than the larger portions of said tapered ends and of greater inside diameter than the smaller portions of said tapered ends, and means to limit the lateral movement of the driven shaft with relation to the driving shaft.

In testimony whereof, I have signed my 80 name to this specification.
